UNITED STATES PATENT OFFICE.

CAMILLE BRUN AND GUSTAVE BRUN, OF LYONS, FRANCE, ASSIGNORS TO
EMIL C. FOERSTER, OF NEW YORK, N. Y.

SHUTTLE.

SPECIFICATION forming part of Letters Patent No. 748,922, dated January 5, 1904.

Application filed May 11, 1903. Serial No. 156,570. (No model.)

To all whom it may concern:

Be it known that we, CAMILLE BRUN and GUSTAVE BRUN, citizens of the French Republic, residing at Lyons, Rhône, France, 5 have jointly invented certain new and useful Improvements in Shuttles, of which the following is a specification.

This invention aims to provide an improved loom-shuttle of the same general character as 10 that described in the application for patent of Brun and Brun, Serial No. 153,435, filed April 20, 1903. It is specially designed for operating or controlling mechanism for stopping the loom or for supplying new weft or 15 for similar purposes. Looms having mechanism of this kind are well known. An example of such a loom is shown in the patent of Brun, Brun, and Bickling, No. 714,655, granted December 2, 1902. The specific im- 20 provements shown in this application are specially designed for operation with the loom mechanism of said patent, though the invention contemplates, broadly, a shuttle adapted for use with various other loom mechanisms. 25 For this purpose the invention provides means in the shuttle for controlling mechanism of the loom and a part of which is adapted to be surrounded by the thread on the spindle and at least the end of said part being 30 substantially within the surface of the spindle when the mechanism-controlling means are inoperative. The position of the end of the part of the device surrounded by the thread facilitates the application of the 35 thread on the spindle without catching under the end of said part.

We have shown in connection with the shuttle mechanism described a quill of special design and material and have shown the 40 spindle of the shuttle of a form particularly adapted for use with said quill, as herein-after described.

Various other features of improvement are specified in detail hereinafter.

45 The accompanying drawings illustrate an embodiment of the invention.

Figure 1 is a plan view of a shuttle with the spindle down and without a quill thereon. Fig. 2 is a horizontal section of the same 50 just above the spindle and showing a quill thereon from which the thread has been ex-

hausted. Fig. 3 is a horizontal section of the same through the center of the spindle. Fig. 4 is a horizontal section of the same with the spindle turned up, the plane of section 55 through the spindle being taken on the line 44 of Fig. 3. Fig. 5 is a longitudinal section of the shuttle, showing the spindle in side elevation. Fig. 6 is a similar section through the center of the spindle. Fig. 7 is a section 60 similar to Fig. 6, but with the spindle raised to the position in which the quill is applied. Fig. 8 is a side elevation of the spindle in the position of Fig. 7 and with the quill applied thereto. Fig. 9 is a cross-section on the line 65 99 of Fig. 8.

Referring to the embodiment of the invention illustrated, the spindle A is pivoted at its heel about a hollow shaft B and is held impositively in its raised or lowered position 70 by means of the usual spring C or any other suitable means. The means for controlling the mechanism of the loom comprises a member illustrated in the form of a pin D, transversely movable and provided with an arm 75 E, the outer portion of which is adapted to be surrounded by the thread on the spindle in the manner explained. The end F of the arm E is preferably tapered, so that the portion of it which is first met by the quill or the 80 thread as the latter is introduced onto the spindle (the arm being moved up against the spindle, as hereinafter explained) is substantially within or flush with the surface of the spindle, which permits the thread and the 85 quill to pass over the end of the arm and to surround a considerable portion thereof, as shown in Fig. 3. Preferably a groove G is formed in the side of the spindle, arranged to register with the end of the arm E when 90 the latter is moved inward, so that the latter may enter the groove and be absolutely within the surface of the spindle. With the parts in this position the arm E, and with it the pin D, are held inward in the inoperative po- 95 sition of the latter against the pressure of the spring H. When the thread is exhausted or so nearly exhausted that its resistance is not sufficient to hold the spring H compressed, the spring moves the pin D outward, and thus 100 determines the operation of the stopping or weft-replenishing mechanism of the loom.

Preferably the pin D is automatically moved inward as the spindle is turned up to the position for supplying a new load of thread. This may be accomplished by the use of a wire cam J, lying in the path of the arm E, the latter being moved up and down with the spindle by means of pins K, projecting from the heel of the spindle and engaging the arm E on opposite sides. This mechanism is claimed in the application of Brun and Brun above referred to.

The shuttle is shown in connection with a thin-walled quill or cop-tube L, of paper or the like, and the longitudinal opening M provided in such quill for registering with the arm E is preferably in the form of a mere slit. The slit M, it will be understood, is to enable the arm E to escape as soon as the thread is so nearly exhausted that it has not sufficient strength to hold the walls of the opening together and to thus hold the arm E in against the spindle in opposition to the action of the spring H, or the opening M may be of appreciable width, so that the thread bears directly on the arm E to hold it in against the spindle. The mechanism described is of special use in connection with such a quill, since it enables the workman to apply this cheap quill to the shuttle quickly and without any special care.

The apparatus may be specially adapted for slotted quills of the kind described or of any other suitable kind by the provision of mechanism (illustrated best in Figs. 5 to 7, inclusive) for spreading the sides of the slit or other longitudinal opening provided. The mechanism shown permits of the application of the quill with the spindle in the upright position, as usual, and upon the turning of the spindle down to the running position automatically brings into action a spring-pressure tending to spread the sides of the opening, so that the arm E or other part of the mechanism - controlling means is substantially free except for its control by the thread. For this purpose the spindle shown is provided with a vertical longitudinal slit in which is an arm N, pivoted at O and adapted at its forward end to swing down to the position shown in Fig. 7, with the lower portion P thereof projecting out of the spindle, or to the position shown in Fig. 6, with its upper edge projecting above the spindle. The portion P is offset, as shown, and lies entirely beyond the lower end of the quill. The parts being in the position of Fig. 7, the quill may be introduced without difficulty, fitting exactly the spindle. As the spindle is turned down, however, the projection P engages a spring-stop consisting of a wire Q extending across the lower part of the shuttle, which engagement tends to throw the end of the arm N upward until the upper edge of the arm projects above the surface of the spindle and to thus spread the slit or other longitudinal opening in the side of the quill. When the quill is first inserted with

the arm N withdrawn, it appears as in Fig. 8. When the arm N is pressed upward, the slit in the quill is enlarged, as in Fig. 5. ⁷⁰ The stop Q may be a transverse wire forming the end of a longitudinal wire R, entering the side of the shuttle at its opposite end and resting at an intermediate point on a pin S, so as to permit a certain amount of yielding of the stop Q proportioned to the resistance of the quill and the thread surrounding it. The end of the arm N may be forked and limited in its movement by a stop comprising a pin T, extending transversely across the slot ⁸⁰ in the spindle. The turning upward of the arm N provides, as will appear from Fig. 6, an extra enlargement of the base portion of the spindle beyond that which would be due to its taper form, and obviously a permanent ⁸⁵ enlargement of this kind might be used for the same purpose, though it would make somewhat more difficult the insertion of the quill on the spindle.

The invention provides also means for holding the quill on the spindle. These means are especially useful in connection with the tapered spindle shown and with the extra enlargement at the base thereof for spreading the longitudinal opening of the quill. ⁹⁰ The means illustrated are especially adapted for the paper quill described. They comprise in the form illustrated an arm U on the same pivot O and moved with and preferably formed integral with the arm N and ¹⁰⁰ provided on its under side with one or more teeth adapted to bite into the material of the quill, and thus hold it from withdrawal. This arm U is pressed down to the engaging position and its teeth are pressed into the ¹⁰⁵ smooth inner surface of the quill as the spindle is turned down and as the projection P engages the stop Q and throws up the arm N in the manner described. This effectively prevents any movement of the quill toward ¹¹⁰ the end of the spindle after it has once been applied.

The functions and modes of operation of the several individual features of the invention being clear, only a brief description of the operation of the complete shuttle and mechanism shown will be necessary. The spindle is first turned up to the position of Fig. 7, the cam J at the same time forcing the arm E to its inward position as the arm is carried up by means of the pins K. The transversely-moving pin D at the same time is moved to its inward position, Fig. 3. The quill, loaded with thread, is then applied and surrounds the end of the arm E, so that as the spindle is turned ¹¹⁵ down the arm E and pin D are held in, with the latter in its inoperative position. As the spindle is turned down the projection P in the quill-spreading device engages the spring-stop Q and presses the upper edge of the arm ¹²⁰ N, so that as the thread runs off the latter gradually moves out beyond the surface of the spindle, spreading the slit M in the quill, as ¹²⁵ shown in Fig. 5. The arm E is then free from

any control by the quill and is held only by the remaining thread. Simultaneously with the upward movement of the arm N the arm U is pressed downward, so that its teeth bite 5 into the quill, as shown in Fig. 6, and prevent longitudinal movement of the latter. When the shuttle has run until the thread is nearly or substantially exhausted, the strength of the spring H overcomes the resistance of the 10 thread and forces out the arm E and the pin D, the latter operating the loom mechanism, as described.

We make no claim in this application to the quill of special design and material described 15 or to the special construction of the spindle for spreading such a quill or for biting into and retaining it on the spindle, these features being claimed in our application, Serial No. 167,730, filed July 31, 1903.

20 Though an embodiment of the invention is described with great particularity of detail, yet it is to be understood that the invention is not limited to the specific embodiment disclosed. Various modifications in detail and 25 in the arrangement and combination of the parts are possible to those skilled in the art without departure from the invention.

What we claim is—

1. In a shuttle in combination, a spindle, 30 means mounted in the shuttle separately from said spindle and adapted to control mechanism of the loom and a part of which is adapted to be surrounded by the thread on said spindle, at least an end of said part being substantially within the surface of the spindle when said means are inoperative, to permit the ready application of the thread onto the spindle.

2. In a shuttle in combination, a spindle, 40 having a groove in its side, means mounted in the shuttle separately from said spindle and adapted to control mechanism of the loom and a part of which is adapted to be surrounded by the thread on said spindle 45 when said means are inoperative, and to be moved into said groove to permit the ready application of the thread onto the spindle.

3. In a shuttle in combination, a spindle, a member extending transversely of the shuttle, transversely reciprocable therein and 50 adapted to control mechanism of the loom,

and an arm on said member adapted to be surrounded by the thread on said spindle, at least the end of said arm being substantially within the surface of the spindle when said member is in its inoperative position, to permit the ready application of the thread. 55

4. In a shuttle in combination, a spindle, a member extending transversely of the shuttle, transversely reciprocable therein and 60 adapted to control mechanism of the loom, an arm on said member adapted to be surrounded by the thread on said spindle, at least the end of said arm being substantially within the surface of the spindle when said member 65 is in its inoperative position, to permit the ready application of the thread, and a cam in the path of said arm and adapted to move the end of said arm inward as the spindle is turned up. 70

5. The combination with a shuttle having a pivoted spindle, of a thin-walled quill of paper or the like for said spindle, means mounted in the shuttle separately from the spindle and adapted to control mechanism of the loom 75 and a part of which is adapted to be surrounded by said quill and the thread thereon to retain said means in inoperative position during normal running of the shuttle.

6. The combination with a shuttle having a 80 pivoted spindle, of a thin-walled quill of paper or the like for said spindle, a hollow shaft for said spindle, a mechanism-controlling pin reciprocable in said hollow shaft, and an arm on said pin adapted to be surrounded by said 85 quill and the thread thereon to retain said pin in its inoperative position during normal running of the shuttle.

7. In a loom-shuttle, in combination, a spindle, a member adapted to control mechanism 90 of the loom, and a device connected at one end to said member and having its opposite end engaged in a slot in the spindle and adapted to be surrounded by the thread to hold said member in inoperative position. 95

In witness whereof we have hereunto set our hands in presence of two witnesses.
